WILLIAM L. DAYTON Inventor

By A. L. Jackson

Altorney

UNITED STATES PATENT OFFICE.

WILLIAM L. DAYTON, OF FORT WORTH, TEXAS.

POWER JACK.

Application filed January 25, 1923. Serial No. 615,441.

My invention relates to power jacks; and the object is to provide simple and powerful jacks for use with air-compressors, pumps, and various machines which may be operated with a crank, and to provide power jacks which are simple in operation and construction and which can be operated with little power. One advantage is that a machine with a small amount of power may be employed so that there will be a saving in fuel and labor. Another advantage is that the power jack is provided with certain automatically shifted weights which effect a saving in power. Other objects and advantages 10 will be fully explained in the following description and the invention will be more particularly pointed out in the claims.

Reference is had to the accompanying drawings which form a part of this application.

Fig. 1 is a side elevation of the improved power jack. Fig. 2 is a plan view of the same. Fig. 3 is a detail view of the gearing for shifting the walking beam for lengthening the strokes. Fig. 4 is a plan view of the same, Figs. 3 and 4 being enlarged views. Fig. 5 is a side elevation of a power jack, including certain variations. Fig. 6 is a plan view of the jack shown in Fig 5.

Similar characters of reference are used to indicate the same parts throughout the several views.

The improved power jack has a two-part frame,—one part being the gearing frame and the other part being the frame for the power levers. The gear frame has duplicate lower beams 1 except that one of the lower beams 1 forms (by an extension) one of the lower beams of the power lever frame. The gear frame has duplicate uprights 2 and duplicate upper longitudinal beams 3 and 4, the beam 3 being connected to one of the upright members 11 of the lever frame. The duplicate beams 1 and the beams 3 and 4 are connected by bolts 6 at the upper and lower parts and these bolts may be provided with sleeves between the beams to space the beams apart. The bolts are provided with nuts 7. The lever frame has uprights 8 and 9 and inclined uprights 10 and 11 which are connected at their upper ends by short longitudinal beams 12. The inclined upright 11 is rigidly connected to the upper beam 3 of the gear frame and rigidly connected to the adjacent lower beam of the gear frame. The lever frame has on one side a lower longi-

tudinal beam 13 and extension of the beam 1 of the gear frame forms a companion beam to beam 13 for the lower frame. The beams 3 and 4 and the inclined uprights 10 and 11 are all connected by a bolt 14 which may have sleeves 16 between the beams and the uprights. A bolt 17 connects the inclined uprights 10 and 11 at the bottom and also connects the beams 1 of the gear frame. Sleeves 18 may be placed on the bolt 17 between the connected elements.

The machine is provided with a power pulley or wheel 19 which is rigid with the shaft 20 and a balance wheel 21 is rigid 70 with the shaft 20. A pinion 22 is rigid with shaft 20 and meshes with and drives a cog wheel 23 which is rigid with shaft 24. A crank 25 is rigid with shaft 24 and this crank is pivotally connected to a pitman 26. 75 The crank 25 is rigid with its bolt 27 and a power lever 28 is rigid with the same bolt 27 so that the crank 25 and the lever 28 move at the same time. The power of the pitman bar 26 is transmitted to a lever or lower walking beam 29 and the power of the lever 28 is transmitted to a pitman bar or rod 39.

A movable or shifting fulcrum bar 31 is pivotally connected to the lower walking beam 29. A pair of bearing and guide members 31' are rigid with the upper end of the fulcrum bar 31. The machine is provided with an upper walking beam 32 and a support 33 is rigid therewith. The support 33 has a gear segment 34 and gear segment 35 90 is rigid with the guide and bearing members 31'. Link bars 36 are pivotally connected to the support 33 and to the bearing members 31'. In this manner, the upper beam 32 is operatively connected to the lower walking beam 29 and the object of this manner of connection is to lengthen the stroke of the upper walking beam and the connecting rod 36'.

Brackets 37 are attached to the walking beam 32 and the connecting rod 36 is pivotally connected to the brackets 37. At the other end of the walking beam 32, brackets 38 are provided and rigid with the walking beam 32. A pitman 39 is pivotally connected to the brackets 38 and to the lever 28. The lever 28 has a number of bolt holes so that the pitman rod 39 may be connected thereto at different adjustments for increasing or decreasing the length of the strokes of the walking beam. The walking beam is provided with a brace rod 40 which is at-

tached to the brackets 37 and 38 and spaced from the beam 32 by an upstanding lug or support 41. Antifriction rollers 42 are provided to prevent friction of the fulcrum bar 31 in its vertical movements.

The power jack shown in Figs. 5 and 6 has frame elements similar to frame elements shown in the previous views and the driving mechanism is the same. The wheel 23 drives a crank 50 which actuates a pitman rod 51 which is pivotally connected to a walking beam 52. The walking beam 52 is actuated from the drive wheel 23. The drive wheel 23 is rigid with shaft 24. A weight 53 is slidably mounted on the beam 52 and provided with antifriction rollers 54 to relieve friction. The beam 52 has a slot 55 therein for the pivot bolt 56.

Means are provided for shifting the weight 53 automatically towards and from the fulcrum 57 of the walking beam 52. A lever 58 is fulcrumed on the frame of the machine by a pivot shaft 59. A link bar 60 is pivotally connected to the lever 58 and 20 pivotally connected to the pitman rod 51. The lever 58 is a two pronged or two armed lever and the two arms of the lever 58 are pivotally connected to link bars 61 and the link bars 61 are pivotally connected to the weight 53. The weight 53 will be moved simultaneously with the moving of the pitman rod 51.

The walking beam 32 is fulcrumed in a pair of levers 62 which are fulcrumed in the 35 upper part of the frame by means of a pivot shaft 68. The levers 62 are pivotally connected to link bars 64 and the link bars 64 are pivotally connected to cranks 65. The wheel 23 will actuate the levers 62 through 40 the cranks 65 and link bars 64. A weight 66 aids in balancing the weight 53.

In operation the weight 53 is shifted to the outer end of the lever or walking beam 52 for the purpose of balancing the weight 45 66, and the object of this action is to obtain the combined effect of both weights in raising the load. On the down stroke of the sucker rod, the weight 53 is automatically shifted to its inward limit and the weight 50 66 goes down and rests on the beam 32 by reason of the lug 67. This action will tend to elevate the outer end of the beam 52. For a portion of the downstroke, the lug 67 55 will bear on the beam 32 and during such time both beams 32 and 52 act as one beam. For a portion of the upstroke, the beam 52 draws the weight 66 up against the beam 32, and during such time both beams act as one beam. The fulcrums 57 and 63 both 60 move during operation. The levers 62 are fulcrumed on a pivot bar or shaft 68. All the levers and link bars and the pitman rod are timed to work in unison with the

drive wheel 23, by reason of the cranks which are actuated by the drive wheel 23. The elements 62 are called levers above, but the two elements form a walking beam and the functions correspond to the functions of the walking beam 29. Various changes in the sizes, proportions, construction and arrangements of the several parts may be made without departing from my invention.

What I claim, is,—

1. A power jack having a power walking beam and an operating walking beam, a power mechanism operatively connected to one end of said power walking beam for actuating the same, a movable fulcrum for said operating walking beam carried by the other end of said power walking beam, and segmental gearing operatively connected to said movable fulcrum and with said operating walking beam for increasing the stroke of said operating walking beam.

2. A power jack having a power walking beam and an operating walking beam, a power mechanism operatively connected to one end of said power walking beam for actuating the same, a fulcrum bearing carried by the other end of said power walking beam for said operating walking beam, segmental gearing operatively connected to said fulcrum bearing and to said operating walking beam, and link bars holding said gearing in operative relation.

3. A power jack having a power walking beam and an operating walking beam, a power mechanism operatively connected to one end of said power walking beam for actuating the same, a fulcrum bearing carried by the other end of said power walking beam for said operating walking beam, gearing operatively connecting said fulcrum and said operating walking beam, and a pitman rod connecting one end of said walking beam to said power mechanism.

4. A power jack having a power walking beam and an operating walking beam, a power mechanism operatively connected to one end of said power walking beam for actuating the same, a fulcrum bearing carried by the other end of said power walking beam for said operating walking beam, a segmental gearing carried by said bearing and a segmental gearing carried by said operating walking beam and engaged by the first named gearing, link bars for holding said gearing in operative relation, and a pitman rod connected to one end of said operating walking beam and to said power mechanism.

In testimony whereof, I set my hand, this 6th day of January, 1923.

WILLIAM L. DAYTON.
